UNITED STATES PATENT OFFICE.

HARRY LANDSIEDEL, OF CINCINNATI, OHIO, ASSIGNOR TO THE DALTON ADDING MACHINE COMPANY, OF CINCINNATI, OHIO, A CORPORATION OF OHIO.

ADDING AND RECORDING MACHINE.

1,225,656.

Specification of Letters Patent.

Patented May 8, 1917.

Application filed April 23, 1916. Serial No. 94,226.

To all whom it may concern:

Be it known that I, HARRY LANDSIEDEL, a citizen of the United States, residing at the city of Cincinnati, county of Hamilton, and State of Ohio, have invented a new and useful Adding and Recording Machine, of which the following is a specification.

This invention relates to adding and recording machines.

10 The machine embodying my invention comprises a series of movable type-carriers and a coöperative series of racks, and mechanism for operating them in recording and adding operations, in combination with 15 mechanism for controlling the differential movements of the type-carriers and racks and comprising differential stops adapted to be set to limit movement thereof, selecting and setting devices for setting the stops, including setting devices under control of 20 revoluble selectors whereby the setting devices may be selectively positioned to set the stops selectively as required to limit movement of the type-carriers and racks so that 25 the proper numbers will be recorded and added as a result of the operation of the type-carriers and racks.

One of the specific objects of the invention is to provide a novel differential mechanism 30 comprising series of differential stops; series of stop setting elements adapted to be moved to position to set the stops; a revoluble selecting and positioning device for each series of stop setting elements whereby the 35 latter may be selectively moved to position to set selected stops, and then returned to their normal positions as an incident to recording or adding operations of the machine; and means for restoring the stops to 40 idle position as an incident to the recording and adding operations.

In the drawings,

Figure 1 is a vertical longitudinal section of an adding and recording machine in 45 which the present invention is embodied.

Fig. 2 is a plan view of the differential mechanism and associated parts.

Fig. 3 is an enlarged side elevation of the differential mechanism.

50 Fig. 4 is a longitudinal sectional view of the differential mechanism.

Fig. 5 is a detailed view of the device for releasing the racks from the latches which normally prevent operation thereof and

which are released by the device illustrated 55 as an incident to the setting of differential stops corresponding to the racks.

Fig. 6 is a transverse sectional view of the differential mechanism.

Fig. 7 is a perspective view of the escape- 60 ment mechanism controlling the operation of parts of the differential mechanism.

Fig. 8 is a view illustrating the mechanism under control of the main shaft for restoring 65 the stop setting devices to normal, and also illustrating the repeat connections for preventing operation of the restoring mechanism.

Fig. 9 is a plan view of the same mechanism, and also the normally operable 70 connections for actuating the stop setting devices toward their normal positions.

The machine in which I have illustrated my invention comprises recording mechanism including a series of type-carriers 1 75 pivotally supported in numerical order by a rock-shaft 2. The type-carriers are co-operatively associated with racks 3 also pivotally supported by the rock-shaft 2 and arranged to operate adding mechanism 4 to 80 add the numbers recorded by operation of the type-carriers. The type-carriers are co-operatively related to hammers 5 adapted to coöperate with the type on the type-carriers to print upon paper supported against a 85 platen mounted in a paper carriage 6. The usual main shaft 7 extends transversely of the machine and is arranged to be rocked or turned in one direction by any device under control of the operator and rocked or turned 90 in the opposite direction by springs 8 connecting an arm on the shaft with some stationary part of the machine.

The type-carriers and racks are normally retained in their rear or idle positions by the 95 usual connections 9 from the shaft 7 to the swinging arms 10 dependent from the rock-shaft 2 and carrying a rod 11 extending transversely in front of the vertical portions of the type-carriers to hold them and the 100 racks in their idle positions in opposition to their actuating springs 12.

Each rack is provided with a projection 13 which is engaged by the hooked end of a latch member 14, said latch members being 105 retained in engagement with the projection 13 by springs 15. The latches 14 are pivoted upon a rod or shaft 16, and the lower

arm of each latch has pin-in-slot connection 17 with a releasing lever 18. The series of levers 18 are pivoted upon a shaft 19 and are movable to release the latches 14 from the racks so that the racks may be operated in clearing operations. Two arms 20 depend from the shaft 19 and support a rod 21 transversely in front of the lower ends of the levers 18, so that by actuating the rod 21 toward the rear the levers 18 will be operated to release the latches 14 from the racks. The link 22 has its rear end connected to the rod 21 and its forward end connected with the usual total key connections 23, so that said link is moved rearwardly in the usual manner as a result of operation of the total key, thus releasing all of the latches 14 from the racks and enabling the latter to operate in clearing operations.

20 In the differential mechanism the stops are arranged in transverse series in which all of the stops in each transverse series represent the same digit; and the stops are also arranged in longitudinal series in numerical orders; and all of the stops are capable of being selectively set in position to limit movement of the type-carriers and racks. As shown there is one longitudinal series of stops 24 for each rack, said stops being supported and guided by the upper and lower plates of a frame 25. The stops 24 are movable longitudinally and are pressed downwardly by springs 26 interposed between shoulders on the stops and the upper plate of the frame. The stops are raisable in opposition to the springs 26 and will be retained in their elevated positions by shoulders 27 on the stops engaging projections 28 on adjacent movable plates 29, as will be understood by reference to Fig. 5. The plates 29 are actuated in one direction by springs 30 connecting the plates respectively with a stationary part of the frame in which the stops are supported. Obviously, by actuating the plates 29 in opposition to the springs 30 the raised stops will be released from said plates and will be depressed by their springs 26.

50 The upper plate of the top frame is provided with slots or grooves 31 in which the extensions 32 on the racks operate. Thus the racks are guided in their movements by the extensions 32 thereon moving within the slots or grooves 31, and movement of the racks is limited by the extensions 32 engaging with the stops 24 which had been selectively set and projected upwardly into the path of movement of said extensions 32. In the embodiment illustrated there are nine 55 stops 24 in each numerical order, there being one of said stops for each of the ten figures or digits, except for the digit 9. For stopping the racks and type-carriers in positions corresponding to the digit 9, a part 60 33 is fixed on the frame 25 across the slots

or grooves 31, so that the extensions 32 will engage therewith.

A series of magazines 34 extend through openings in the frame parts 35 in such position that the inner ends of the magazines 70 open above the revoluble selecting and positioning devices 36. The upper part of each magazine is flared at its inner end as shown at 34^a. Each magazine is actuated downwardly by a coil spring 34^b, encircling the 75 magazine between the part 35 and a collar 34^c on the magazine (Fig. 6). There is one of the devices 36 and one of the magazines 34 for each digit series or transverse series of stops 24, and said devices are supported 80 below the lower ends of said stops. One end of the devices 36 is supported by the frame part 35 and the opposite end of said devices is supported by a part 37. The devices 36 are formed with spiral grooves 85 spaced or pitched in conformity with the stops 24 so that when the stop-setting elements are moved by the devices 36 they will unfailingly be positioned directly below and in longitudinal alignment with the lower 90 ends of the stops 24. The selecting and positioning devices 36 are entrained by intermeshing pinions 38 so that when one of said devices, which is in communication with the escapement mechanism is operated, all of them will be equally operated. One of the pinions 38 is in mesh with a larger pinion 39 upon an escapement shaft 40 which also carries the escapement ratchet wheel 41.

95 The escapement shaft 40 may be intermittently actuated in one direction by any suitable actuating spring or motor of the type usually employed for actuating such shafts. I have illustrated a novel form of device which automatically actuates the shaft in its escapement movements, and connections for actuating said devices to propel the escapement shaft in the opposite direction to its starting point. This device is hereinafter described in detail.

100 The step-by-step rotation of the ratchet 41 is controlled by two oscillating pawls 42 acting in the usual manner to control the rotation of the escapement ratchet and shaft. The pawls 42 are supported by a 105 rock-shaft 43 having an arm 44 attached to one end thereof and a link 45 pivoted to said arm. The opposite end of the link 45 is pivoted to an arm 46 attached to a rock-shaft 47. An extension of the arm 46 supports one end of a rod or universal bar 48, the opposite end of which is supported by a lever 49 (Fig. 7) which is actuated downwardly by a spring 50.

110 The machine in which I have illustrated 115 the invention includes ten numeral keys 51, which are arranged in a convenient key board upon the protruding ends of key levers 52. The inner end of the lever 49 rests upon the key lever corresponding to 120

130

the digit 9 so that when the "9" key is depressed and the rear end of the key lever 52 is raised, the arm 49 will be raised, thus rocking the shaft 47 and, through the connections from said shaft comprising the arm 46 on the link 45, the escapement will be operated one step or space for each depression of the "9" key. Each of the remaining key levers 52 coöperates with an independent lever 53, so that when any one of the remaining numeral keys is depressed, the corresponding lever 53 will be raised without interfering with any of the other levers 53. The levers 53 are pivoted upon a shaft 54 and they extend under the universal bar 48, as a result of which arrangement the escapement mechanism will be operated at each depression of a numeral key. Since the escapement mechanism is operated in the manner described at each depression of any numeral key, the selecting and positioning devices 36 are also operated.

As stated, there is one of the magazines 34 for each digit series of stops 24, and each magazine contains a series of stop setting elements 55. The levers 53 are formed with arms 56 extending downwardly adjacent to the inner ends of the magazines 34 in position to engage the lower ends of the magazines and hold them in their outward positions against the tension of the springs 34^a so that the flared portions 34^a will impart no pressure against the elements 55. Since the elements 55 are thus loosely supported and are held by the arms 56 they cannot be moved by the positioning devices 36 when the latter operate, except when the corresponding numeral key lever is operated to raise the arm 56 of one of the levers 53, in which case the magazine 34 will be passed inwardly by its spring 34^b and the lower element 55 will be released and moved laterally by the positioning device 36 to a position immediately below the lower end of the corresponding stop 24 in units order. Thus, the elements 55 are selectively released from their magazines and placed under control of the positioning devices 36. Since all of the positioning devices are entrained and are operated simultaneously, the elements 55, released in this manner, will be moved from order to order under the corresponding stops 24. When all of the elements 55, corresponding to the digits of the number to be added or recorded, have been positioned under their corresponding stops, it is necessary then to actuate the main shaft 7 to enable the racks and type-carriers to move to the positions indicated by the elements 55 and to set the stops 24 corresponding to said elements, so that the type-carriers and racks will be stopped. It is also necessary to release the latches 14 from the racks which are to operate. Said

latches are automatically released, one by one, by a device operated as an incident to operation of the numeral keys.

In the embodiment shown the releasing device includes a plate 57 (Fig. 5) supported by the frame parts 35 and 37 and provided with a tongue 58 engaging the adjacent spiral and selecting device 36, so that when the selecting device is rotated as an incident to the depression of any numeral key, the plate 57 will be moved laterally toward higher numerical orders. Said plate is provided with a cam shoulder 59 engaging the edges of the latch releasing levers 18 which are thereby operated to release the corresponding latches 14 from engagement with the racks. Obviously, rotation of the positioning devices 36 in the opposite direction will restore the plate 57 to its starting point and enable the latches to reengage the racks.

The manner of setting the stops 24 by the elements 55 will now be described. The frame 25 is supported by rollers 60 extending into slots formed in the sliding supporting plates 61. The slots in which the rollers 60 operate have depressed portions 62 so that when the plates 61 are actuated forwardly toward the key-board of the machine, the frame 25 will be drawn downwardly when the rollers 60 enter the depressed portions 62 of the slots, thus engaging the lower ends of the stops 24 with any of the stop positioning elements 55 which had been positioned in alignment therewith as described. The forward ends of the plates 61 have extensions in which are formed arcuate slots 63 and vertical slots 63^a in communication therewith. Arms 64 attached to the main shaft 7 have projections 65 extending into the vertical slots 63^a so that when the shaft 7 is turned in a forward direction, the plates 61 will first be actuated forwardly until the projections 65 leave the vertical slots 63^a and enter the arcuate slots 63. This movement of the plates 61 is effected before the type-carriers and racks are released by the rod 11 so that the frame 25 is lowered and again raised before the racks begin to move. When the frame 25 is lowered the stops 24, which are in alignment with the stop positioning elements 55 that had been set as described, are forced upwardly in opposition to the springs 26 and are latched in their raised positions by the shoulders 27 on the stops engaging the projections 28 on the latch plates.

The further movement of the main shaft 7 actuates the rod 11 to release the type-carriers and racks which then move to the positions determined by the stops 24 set in the manner described.

The frame 25 is held from horizontal movement by arms 66 carried by a shaft 67 supported by the frames of the machine and

having their forward ends pivotally connected to the frame 25.

The devices for actuating the escapement shaft 40 in its escaping movements operate automatically as hereinbefore stated and are operated in a reverse direction by connections under control of the main shaft 7 during return movement of the latter after the racks and type-carriers have been stopped 10 in their forward positions.

In the embodiment shown a pinion 68 is attached to a sleeve 69 fast on the shaft 40 and having a pawl-supporting part 70 in connection therewith. A pawl 71 is supported by the part 70 and engages a ratchet wheel 72. The ratchet wheel 72 and the escapement ratchet wheel 41 are both connected to a sleeve 73 which is loose on the escapement shaft 40. In this way the escapement shaft is held from rotation and is controlled in its step-by-step rotary action by the escapement ratchet wheel 41 and its connections with the parts which are rigid on the shaft 40, the intermittent action being permitted by the operation of the escapement pawls 43, as will be readily understood. It will also be apparent that reverse rotation of the shaft 40 can be effected independently of the escapement ratchet wheel 41. A rack 74 pivoted upon a support 75 meshes with the pinion 68 and is actuated by a spring 76 connecting an arm on the rack with a stationary part of the machine frame, so that when the escapement pawls 35 are operated as a result of operation of the numeral keys, the escapement shaft will be intermittently actuated by said rack under the influence of the spring 76.

Optionally operable connections for storing the stop setting elements 55 into their magazines are provided. These connections include a depressible key 77 conveniently arranged in the key-board and operatively connected with a lever 78 (Fig. 1). The inner end of the lever 78 is connected by a link 79 with an arm 80 attached to a rock-shaft 81 and having a depending arm 82 in connection therewith. A link 83 has its forward end pivoted to the lower end of the arm 82 and its rear end connected with an extension of the rack 74 by pin-in-slot connection 84. This connection permits the rack 74 to be actuated under the influence of the spring 76, without interfering with the connections just described and, by depression of the key 77, the connections may be operated to cause the rack 74 to operate the escapement shaft 40 and thereby the spiral selecting and positioning devices 36 as required to return the stop setting elements 55 into the magazines 34.

The stops 24 which had been latched in set position to limit movement of the racks are automatically released by the backward or return movement of the plates 61, after

each item has been added or recorded. For the purpose of effecting the release of the stops there is a universal bar 85 supported by two arms 86 carried by a rod 87. The bar 85 extends transversely adjacent to the forward ends of the plates 29 and is engaged by a projection 88 (Fig. 4) on one of the plates 61. As the plate 61 is returned to its normal position by the return movement of the rock shaft 7 and the connected parts, the rod 85 is engaged by the projection 88 and is moved a sufficient distance to actuate all of the plates 29 far enough to disengage the projections 28 from the projections 27. This movement of the rod 85 may be effected by inclining the rear wall of the slot 63^a where it opens into the slot 63 (Fig. 1) so that the plate 61 is moved rearwardly by the projection as said projection enters the slot 63^a a sufficient distance to cause the rod 85 to actuate all of the plates 29 and unlatch the stops as above explained. When the projection 65 enters the slot 63^a it passes into the upper rearward portion of said slot and thereby moves the plate 61 a slight distance forwardly sufficient to afford free latching movement of the plates 29 under control of the stop setting elements 55 and the springs 30, as hereinbefore described, to latch the stops in their raised or set positions. Furthermore, free latching movement of the plates is also afforded by the fact that the stops 24 are not raised until after the plates 61 have started to move forwardly under control of the projections 65, thus moving the projection 88 away from the rod 85.

The stop setting elements 55 may be automatically returned into their magazines by mechanism under control of the main shaft 7 during the backward or return movement of said shaft; or said elements may be retained in their adjusted positions for "repeating" purposes, as desired. I will first describe the mechanism for automatically returning the stop setting elements into their magazines. An arm 89 is supported on the pivot 75. A link 90 (Figs. 7 and 8) has its rear end pivoted to said arm and is provided with a shoulder 91 above which is a forward extension 92. The extension 92 rests upon a projection 93 carried by the arm 64 toward the left of the machine. A hook 94 has its rear end pivoted to the link 90 and its forward end supported by a spring 95 connecting the hook with the extension 92. By reference to Fig. 8 it will be understood that, by this construction, forward turning of the shaft 7 will cause the projection 93 to engage the hook 94 and move the link 90 forwardly until the shaft stops. This forward movement of the link 90 causes the arm 89 to engage a projection 96 on the rack 74 so that the rack will thereby be actuated to rotate the shaft 40, thus 130

turning the positioning devices 86 in a direction to move the stop setting elements 55 into their magazines. This return of the stop setting elements 55 is effected during 5 forward movement of the shaft 7 and is timed so that it occurs after the stop frame has been lowered and the stops have been set by engagement with the proper setting elements.

10 This return movement of the setting elements may be prevented at the option of the operator so that said elements which had been positioned will remain in position to re-set the stops at the next operation of 15 the machine. It is only necessary to prevent the projection 93 from engaging the hook 94 in order to enable the machine to be operated while the stop setting elements remain stationary. Engagement of the projection 93 with the hook 94 is prevented by 20 a manually operable device comprising a hook 97 movable into engagement with a projection 98 on the hook 94 so as to hold the hook 94 in opposition to the spring 95 25 and enable the projection 93 to pass above the hook 94. The connections for operating the hook 97 include a depressible key 99 mounted in a convenient position in the key board and having its stem pivoted to one 30 arm of a bell crank lever 100 and the other arm pivoted to a link 101, the rear end of which is connected to the hook 97. Thus depression of the key 99 will draw forwardly 35 the hook 97 and engage it with the projection 98 and enable the machine to be operated without returning the stop setting elements into their magazines. Any suitable spring devices may be provided for holding the manually operable connections 40 in position so that the hook 97 is normally disengaged from the projection 98.

It will be apparent that the mechanism described may be produced in various embodiments and modified in different respects 45 without departing from the spirit of the invention. I do not restrict myself to specific features of construction and arrangement, but what I claim and desire to secure by Letters Patent, is:—

50 1. In an adding and recording machine, a movable support, series of differential stops mounted in said support, stop setting elements, mechanism for moving said stop setting elements to position in alinement with 55 said stops, mechanism for moving said support to engage stops therein with the setting elements positioned as aforesaid, magazines for receiving said stops, and means for actuating said stops into said magazines.

60 2. In an adding and recording machine, a series of stops for each of several digits, stop setting elements for the stops of each digit, means for supporting the stop setting elements corresponding to each digit separate from the elements corresponding to the

other digits, mechanism for selecting and moving said elements from their supports and positioning them in alinement with the stops, a movable support in which said stops are mounted, and means for moving said support to engage the stop setting elements 70 in alinement therewith.

3. In an adding and recording machine, the combination with a number of positioning devices and corresponding respectively to each of several digits, an actuator for operating said devices simultaneously, a series of stop setting elements under control of each of said devices, and optional means for placing said elements under control of said devices, of a movable support, stops in said support, and means for moving said support 75 to engage stops therein with the elements which had been positioned by said devices.

4. In an adding and recording machine, 80 the combination of positioning devices corresponding respectively to each of several digits, a series of parts adapted to be positioned by each of said devices, means for supporting said parts out of control of said devices, means for placing said parts selectively under control of said devices, an actuator for operating said devices to move the parts controlled thereby to selected positions, series of differential stops, and mechanism for setting those of said stops which 85 correspond to the parts positioned by said devices.

5. In an adding and recording machine, 90 the combination of positioning devices corresponding respectively to each of several digits, a series of stop setting elements adapted to be positioned to represent numbers, means for supporting said elements out of control of said devices, means for selectively placing said elements under control 95 of said devices, an actuator for operating said devices to move said elements to position to represent numbers, differential stops adapted to be set to represent numbers, a 100 movable support for said stops, and means for actuating said support to engage stops therein with the stop setting elements positioned as aforesaid.

6. In an adding and recording machine, 105 the combination of positioning devices corresponding respectively to each of several digits, a series of stop setting elements adapted to be positioned to set stops corresponding thereto, a support for supporting 110 said elements out of control of said devices, means for placing said elements selectively under control of said devices, an actuator for operating said devices as an incident to the placing of said elements under control 115 thereof, a series of stops for each of several digits, a movable support in which said stops are mounted, means for operating said support to engage stops therein with corresponding stop setting elements, whereby 120 125 130

said stops will be set in operative position, and means for restoring said stops to their starting points.

7. In an adding and recording machine, 5 series of differential stops, reciprocating printing elements positioned by said stops, series of laterally movable stop setting elements for setting said stops to position said elements, a rotary positioning device for 10 each series of elements, mechanism for operating said positioning devices to position said elements in alinement with selected stops, and mechanism for causing the elements so positioned to set corresponding stops in operative position.

8. In an adding and recording machine, 20 series of differential stops, reciprocating printing elements positioned by said stops, series of laterally movable stop setting elements for setting said stops to position said elements, a rotary positioning device for each series of elements, means for operating said positioning devices to position said elements selectively in alinement with the selected stops, and mechanism for causing said elements to set the stops in alinement therewith and for restoring said elements to their starting points.

9. In an adding and recording machine, 30 the combination of a series of reciprocating elements, means for actuating said reciprocating elements in opposite directions, series of stops movable into and out of position to limit movement of said elements in one direction, series of setting elements for setting said stops in position to limit movement of said reciprocating elements in one direction, a revolute actuator for each series of said setting elements, and means 40 for operating said actuators to move said setting elements to position to set said stops.

10. In an adding and recording machine, 45 the combination of a series of reciprocating elements, mechanism for operating said elements in opposite directions, series of stops movable into and out of position to limit movement of said reciprocating elements in one direction, a series of stop setting elements for each series of stops, a revolute actuator for moving said setting elements into and out of position to set corresponding stops, mechanism for operating said actuators to move said setting elements into position to set stops, and mechanism for 55 setting the stops by the setting elements moved as aforesaid.

11. In an adding and recording machine, 60 the combination of a series of reciprocating elements, means for actuating said reciprocating elements in opposite directions, series of stops movable into and out of position to limit movement of said elements in one direction, a series of stop setting elements for each series of stops, an actuator for each series of stop setting elements, mechanism

for selecting the setting elements to be actuated and for operating said actuators to move said setting elements to position to set corresponding stops, mechanism for setting stops by the setting elements positioned 70 as aforesaid, and mechanism for operating said actuators to move said setting elements to their starting points.

12. In an adding and recording machine, 71 the combination of a series of reciprocating elements, and means for actuating said reciprocating elements in opposite directions, of differential stops movable into and out of position to limit movement of said reciprocating elements in one direction, a 80 revolute actuator corresponding to each series of stops, a series of stop setting elements controlled by each actuator and movable thereby to position to set selected stops in the corresponding series, means for actuating the stops to set position by the setting elements after said elements have been positioned as aforesaid, and mechanism for operating said actuators to move the stop setting elements to their starting points as 90 an incident to operation of said reciprocating elements.

13. In an adding and recording machine, 95 the combination with a series of reciprocating elements, and means for operating said reciprocating elements in opposite directions, of series of stops for limiting movement of said reciprocating elements in one direction, a series of stop setting elements for each series of stops, a revolute actuator for each series of setting elements, means for operating said actuators, means for selectively placing the stop setting elements under control of the actuators, means for setting stops corresponding to the elements placed under control of the actuators, latches holding the stops in set positions, and mechanism for releasing said latches as an incident to operation of said reciprocating elements. 105

14. In an adding and recording machine, 110 the combination with series of stop setting elements, guides in which said elements are movable to position to represent numbers, and a rotary positioning device operable to move each series of elements to position to represent numbers, of stops supported in alinement with the elements positioned as aforesaid, mechanism for setting said stops by the elements in alinement therewith, 120 latch devices holding the stops in set positions, means for releasing said latch devices, and means for restoring the stops to their starting points.

15. In an adding and recording machine, 125 the combination with series of stop setting elements adapted to be positioned to represent numbers, a rotary positioning device operable to move each series of elements successively and selectively to position to rep- 130

- resent numbers, optional means for bringing said elements successively under control of said positioning devices, and means for operating said positioning devices, of stops supported in alinement with the elements positioned as aforesaid, means for moving said stops into and out of engagement with the elements positioned as aforesaid to set the stops to position to represent numbers, and mechanism for restoring the stops to their starting points while the stop setting elements remain in position to set stops in a succeeding operation.
16. In an adding and recording machine, the combination with series of stop setting elements, a rotary positioning device for each series of said elements, mechanism for selectively bringing said elements under control of said positioning devices, and mechanism for operating said positioning devices concurrently whereby the selected elements will be maintained in proper relative positions, of differential stops adapted to be set to represent numbers, a support in which said stops are mounted; and mechanism for actuating the said stops to set position by the elements positioned as aforesaid, and restoring said elements to their starting points.
17. In an adding and recording machine, the combination with series of stop setting elements movable to and from operative positions, an actuator for each series of elements, means for selectively bringing said elements under control of said actuators, means for operating said actuators, and guides in which said elements are movable, of differential stops adapted to be set to represent numbers, springs actuating said stops in one direction, means for setting said stops by the elements under control of said actuators, latches holding the stops in set positions, mechanism for releasing said latches, and mechanism for operating said actuators to move said setting elements to their starting points.
18. In an adding and recording machine, the combination with series of stop setting elements adapted to be moved to and from operative positions, a rotary positioning device for each series of elements, mechanism for selectively bringing said elements under control of said positioning devices, and mechanism for operating said positioning devices to place the selected setting elements in operative position, of stops adapted to be set to represent the digits of numbers, means for setting said stops by the elements positioned as aforesaid, means for returning the stops to their starting points, and mechanism for operating said positioning devices to return the setting elements to their starting points.
19. In an adding and recording machine, the combination with a series of stop setting elements, a rotary actuator for each series of elements, mechanism for selectively bringing said elements under control of said actuators, mechanism for operating said actuators concurrently to place said elements in operative position, of stops, means for setting said stops by the elements which are placed in operative position as aforesaid, automatic means for operating said actuators to return said elements to their starting points, and optionally-operable manipulative means for operating said actuators to return said elements to their starting points.
20. In an adding and recording machine, the combination with a series of stationary supports, a series of stop setting elements on each of said supports adapted to be moved therefrom to operative position, mechanism for selectively moving said elements from said supports, actuators for moving said elements to operative position, and means for concurrently operating said actuators, of stops adapted to be set to represent numbers, means for setting stops by the elements positioned as aforesaid, latches for supporting the stops in set position, automatic means for releasing said latches, automatic means for operating said actuators to return said elements onto said supports, and optional means for preventing the last-named operation of said actuators.
21. In an adding and recording machine, the combination of a series of stationary supports, a series of stop setting elements supported by each of said supports and adapted to be moved therefrom to operative positions, mechanism for selectively moving said elements from said supports to selected operative positions, stops, means for setting said stops by the elements positioned as aforesaid and as an incident thereto returning said elements to their starting points, and optional devices for preventing said mechanism from returning said elements to their starting points.
- In witness whereof, I have signed this specification in the presence of two subscribing witnesses.
- HARRY LANDSIEDEL.
- Witnesses:
- BENNY DYSART,
R. C. HARRISON.
